C. KITSCHELT.
CLOCK FRONT.

No. 15,997.

Design No. 15,997, dated March 24, 1885.

UNITED STATES PATENT OFFICE.

CHARLES KITSCHELT, OF NEW YORK, N. Y., ASSIGNOR TO NICHOLAS MULLER'S SONS, OF SAME PLACE.

DESIGN FOR A CLOCK-FRONT.

SPECIFICATION forming part of Design No. 15,997, dated March 24, 1885.

Application filed February 11, 1885. Term of patent 3½ years.

To all whom it may concern:

Be it known that I, CHARLES KITSCHELT, of the city, county, and State of New York, have invented a new and original Design for 5 Clock Fronts, of which the following is a full, clear, and exact description, reference being had to the accompanying photograph, making part of this specification, which fully shows the nature of my design.

10 The design relates to an ornamental clock-front; and it consists of a dial having a central rosette and a representation of hammered plate of square shape surrounding said dial, said plate having inwardly-bent overlapping corners and raised ornaments representing 15 different kinds of fruit intermediately between the inwardly-bent corner-pieces.

Referring to the photograph, A represents the dial, and B a representation of hammered 20 plate of square shape that surrounds the dial, which together form a clock-front. The center of the dial A has an ornamental rosette,

C. The representation of hammered front B has inwardly-bent and overlapping corner-pieces B', and intermediately between the 25 same raised ornaments D, representing different kinds of fruits.

Having thus described my design, I claim as new and desire to secure by Letters Patent—

The design for a clock-front, consisting of a 30 dial having a central ornamental rosette, a representation of hammered plate of square shape surrounding said dial, said plate having inwardly-bent and overlapping corner-pieces and raised ornaments representing 35 different kinds of fruit intermediately between the corner-pieces, as shown and described.

In testimony that I claim the foregoing as my invention I have signed it this 27th day of December, 1884.

CHARLES KITSCHELT.
